(57) **CLAIM**

The ornamental design for a faucet body, as shown and described.

DESCRIPTION

FIG. 1 is a top front perspective view of a faucet body in accordance with my invention;

FIG. 2 is a front elevational view of the faucet body;

FIG. 3 is a left side elevational view of the faucet body, the right side being a mirror image thereof;

FIG. 4 is a rear elevational view of the faucet body;

FIG. 5 is a top plan view of the faucet body;

FIG. 6 is a bottom plan view of the faucet body; and,

FIG. 7 is a left side elevational view of the faucet body with the handle shown in its raised position.

The broken lines in the Figures are for illustrative purposes only and form no part of the claimed design.
